(57)

CLAIM

The ornamental design for a pouch, as shown and described.

DESCRIPTION

FIG. 1 is a perspective view in accordance with a pouch design;

FIG. 2 is a front view of the design of FIG. 1;

FIG. 3 is a rear view of the design of FIG. 1;

FIG. 4 is a right side view of the design of FIG. 1;

FIG. 5 is a left side view of the design of FIG. 1;

FIG. 6 is a top view of the design of FIG. 1; and,

FIG. 7 is a bottom view of the design of FIG. 1.

(Continued)

The broken lines are for environment purposes only and form no part of the claimed design. The pouch has no specific size.

1 Claim, 6 Drawing Sheets
